Wesley Clark
By Attorney V. H. Rockwood

UNITED STATES PATENT OFFICE.

WESLEY CLARK, OF SPARTANBURG, INDIANA.

DESK.

SPECIFICATION forming part of Letters Patent No. 549,347, dated November 5, 1895.

Application filed May 8, 1895. Serial No. 548,622. (No model.)

To all whom it may concern:

Be it known that I, WESLEY CLARK, of Spartanburg, county of Randolph, and State of Indiana, have invented certain new and useful Improvements in Desks; and I do hereby declare that the following is a full, clear, and exact description thereof, reference being had to the accompanying drawings, in which like letters refer to like parts.

10 My invention relates to a teacher's desk, and has for its object the combination of parts to render the same more convenient and useful than prior desks of the same character.

15 My invention relates chiefly to two features of this desk—attaching to the rear of the desk cases for letter-blocks and a map-holder. The nature of these features of my invention will appear more fully from the following description and the accompanying drawings.

20 Figure 1 is a perspective view of the front and top of my desk. Fig. 2 is a perspective of the rear with the letter-block cases open. Fig. 3 is a side elevation of the upper rear portion of the desk. Fig. 4 is a detail of the 25 dictionary or book holder and its combination with a desk.

25 My desk 1 is provided with suitable doors, drawers, and closets for the retention of such articles as teachers usually have. In the rear 30 part of the desk, on the side facing the pupils in the school-room, I provide means for using a letter-block device substantially of the same character as that shown in my Letters Patent No. 466,296, issued December 29, 1891. The 35 letter-blocks are secured, as shown in that patent, in boxes, which boxes are secured in the cases 2. There are two of these hinged at one end to blocks 3, that slide in the guide-way 4, made longitudinally in the brackets 5, 40 formed on the rear face of the desk, the upper one of which is preferably hinged. The shelves for the reception of the blocks in the cases 2 are placed on the inner side, the outer side of the cases being plain, like the back 45 of any desk.

50 In use the cases are swung open, as shown in Fig. 2. Blocks are taken from the block-storage case made in the rear portion of the desk and such as are desired are placed in the cases 2, and then the blocks 3, to which

the cases are hinged, are moved in the guide-way toward the end, whereby the cases 2 can be reversed, presenting the face of the blocks to the pupils. A chart-holder is also provided, which consists of a frame 7, having a vertical 55 aperture, so the frame may slip down over the pin 8 in the block 9, that is provided with lateral extensions 10, which work in a suitable groove made by the cleats 11, one on each side of the extension 13 in the upper part of the 60 desk. By this construction the various parts are readily detached, if desired. 12 are fingers or holders pivoted at their upper ends to the frame 7 and held against such frame at the lower ends by the springs 13'. These 65 fingers, in combination with a suitable construction at the lower end of the frame 7, provide means for holding a map-rod. When the map-rod is to be inserted or removed, the fingers 12 are drawn backward, and when released they come together and hold the map 70 in place.

In the upper part of the desk is a case or box 13, containing a dictionary-holder. This consists of a block 14, which slides in and partially out of the case, being held by the stop 15 from being entirely removed. Hinged to the front end of this block is the dictionary-holder, which consists of the base 16, with sides 17 hinged thereto, and a suitable knob 18. 80 The holder when open appears as shown in Fig. 1. It is closed by folding together the sides and then folding the holder forward onto the block 14, and then pushing the whole in the case. When the holder is desired to be 85 brought out, one takes hold of the knob 18 and draws the whole thing toward him until stopped by the stop 15, and then with a slight further pull the holder turns down again into the position shown in Fig. 1, and the sides are 90 then opened.

It is thus apparent that I have a very convenient and useful combination teacher's desk. The parts combined therewith which I have described are always needed and are 95 combined in the most convenient way for actual use.

What I claim as my invention, and desire to secure by Letters Patent, is—

1. The combination with a desk of a letter 100

block case, suitable guide ways in the desk, and blocks sliding in such guide ways, the letter block cases being pivoted at their inner ends to such sliding blocks, substantially as shown and described.

2. The combination of a desk, receptacles for storing letter blocks in its rear part, a pair of suitable guide ways secured to such desk, sliding blocks in such guide ways, and letter block cases pivoted at their inner ends to such sliding blocks substantially as shown and described.

3. The combination of a desk with a guide way on its upper part, and a map holder provided with extensions adapted to move in such

guide way, substantially as shown and described.

4. The combination of a desk provided with a guide way on its upper part, a frame combined with said desk by extensions fitting in the slide ways, fingers pivoted at their upper ends to such frame and adapted to hold a map at their lower ends, and springs connecting such fingers and the frame.

In witness whereof I have hereunto set my hand this 26th day of March, 1895.

WESLEY CLARK.
